WELL CLEANER

Filed Oct. 6, 1934

UNITED STATES PATENT OFFICE

2,052,006

WELL CLEANER

Claude C. Taylor, Whittier, Calif.

Application October 6, 1934, Serial No. 747,161

14 Claims. (Cl. 166—20)

This invention relates to cleaners for oil well screens or perforated casing, as well as to devices for removing from producing strata debris consisting principally of paraffin or asphaltic bodies, rotary mud and other impediments which tend to clog the pores of the oil sands and seriously retard the flow of oil.

Rock pressure in a flowing well may be counteracted by the solidification of such debris in important pressure fissures of the oil sands and the normal pump suction from the well surface is seldom sufficient to remove such accretions, particularly in sands producing high gravity oil.

Various means for applying chemical solvents of various kinds to clogged screen perforations and oil producing strata have been evolved but have met with little success due to a lack of proper application.

A general object of the present invention is to provide a device which may be inserted into the casing (being carried at the end of a drill pipe or tubing) which will, by the systematic agitation of fluid in the well with or without the addition of solvents pumped in from the surface successively loosen such accretions of debris from the perforations in the casing or well screen and from the pores of the oil sands respectively, subsequently drawing said dissociated debris into the casing through cleaned perforations for later removal.

Another general object is to provide such a device which can be run and operated by the ordinary well pulling equipment and crew without the aid of pumps or any other surface or subsurface accessories.

A particular object of my invention is the provision of a series of packers to seal off predetermined sections of the casing opposite producing oil sands and to simultaneously create fluid pressure between one pair of packers and suction between a second pair of packers through the relative movement of said packers, thus to create a more pronounced surging action of fluid within the well.

A still further object is to provide a means for optionally circulating a chemical solvent such as petroleum distillate or a solution of muriatic acid or of soda ash pumped from the surface of the well through perforations in a restricted section of the casing, over a predetermined area of the exposed oil producing strata and return such solvent by powerful suction within the casing through a second set of perforations therein.

Other objects and advantages of the present invention will be apparent to those of skill in this

art and include ease and efficiency of operation, surety of action, economy of manufacture and an elimination of automatically actuated elements resulting in positive control.

The objects and advantages referred to above may be attained by the exemplification of my said invention shown in the accompanying drawing, in which,—

Fig. 1 is a view of the upper section of my invention partly in elevation and partly in longitudinal section;

Fig. 1a depicts a view similar to Fig. 1 of an intermediate section thereof;

Fig. 1b is a like view of the lower section of my invention, each successive figure of the drawing being illustrated to follow below the preceding figure as indicated by connecting arrows.

Referring to the drawing in detail, the numerals of which designate similar parts throughout the several views, 5 indicates a perforated well casing or screen of a conventional type having 20 therein perforations 6 for the admission of oil into the casing.

A drill pipe or tubing 7, comprising a plurality of sections 7' held together by pipe couplings 8, is provided, to spaced sections 7', of which tubing, a pair of packers 9 and 10 are secured in longitudinally immovable position, said packers slidably fitting the casing 5.

A section 11 of drill pipe 7 having a smaller 30 outside diameter than that of pipe sections 7' supporting packers 9 and 10 is connected to lowermost section 7' by reducing coupling 12, below packer 10. A third packer 13 is mounted on a sleeve 14 which is slidably mounted on section 11 of drill pipe 7. The upper end of said sleeve 14 is provided with a stuffing box 15 containing packing material 16 adapted to be pressed by a gland 17, in order to provide a tight sliding fit of the tubing or drill pipe through the anchored 40 packer and its associated parts about to be described.

An anchoring device of a type well known in the art is provided which includes a slip-expanding element 18 screw-threaded between upper and 45 lower sections of sleeve 14, said slip expanding element having a series of outwardly inclined faces 19, on which faces slips 20 carrying downwardly directed teeth 21 are slidably secured by dove-tailed tongue and groove means well 50 known in the art.

A second sleeve 22 is slidably mounted on the lower section of sleeve 14 on which a plurality of outwardly bowed springs 23 are secured to frictionally engage the wall of the casing. 24—24 55

indicate links which secure slips 20 to sleeve 22 in a manner and by means well known in the art. Thus any relative downward movement of sleeve 14 with respect to sleeve 22 will wedge the slips 20 between inclined faces 19 of said slip-expander 18 and the wall of the casing, thus forcing the teeth 21 of said slips into engagement with the casing wall and preventing any further downward movement of the expander 18, sleeve 14 (to which the expander is secured) and packer 13.

To maintain the slips in non-engaging position while lowering the device in the well a bayonet slot 25 is provided in sleeve 22 into which a stud 25a on sleeve 14 extends. Screw-threadedly secured to the bottom of sleeve 14 is a collar 26 the lower edge of which is cut-away to provide shoulders 27. On the extension of the drill pipe or tubing 11 below collar 26 (through which collar 26 said drill pipe slidably passes) a collar 28 is screw-threaded, which collar is provided with upwardly extending shoulders 29 adapted to engage and lock with downwardly directed shoulders 27 on collar 26 when drill pipe 7 is raised relative to packer 13 and its adjacent elements.

As the device is being placed in position within the well, stud 25a is at the outward end of the horizontal leg of bayonet slot 25, in which position the slips are locked out of engagement with the casing, and while being lowered to position the entire packing and anchor-mechanism slidably mounted on the extension of the drill pipe, is raised relative to said drill pipe by the frictional engagement of springs 23 with the casing screen wall.

When the desired anchoring position in the well screen is reached, the drill pipe is raised, packer 13 and anchoring mechanism remaining stationary until collar 28 contacts collar 26 when a slight rotary movement of the drill pipe will turn stud 25a out of engagement with the horizontal leg of bayonet slot 25 and a further longitudinal movement, the slip mechanism being relatively retarded in movement by the bowed springs, will wedge the slip expander 18 downwardly between the slips causing their teeth to engage the casing, the operation of which quite similar anchoring devices is well known in art and therefore need not be more minutely described.

Screw threaded to collar 28 is an extension 30 of the drill pipe or tubing 11, said extension 30 being preferably of larger diameter than said drill pipe or tubing 11. Carried by said extension 30, being held against longitudinal movement with respect thereto, is a packer 31 which slidably fits the interior of the perforated casing or well screen 5. 32-32 indicates open ports through extension 30, and 33 indicates a back pressure valve which may be of any suitable form well known in the art but which I have illustrated as of the poppet type, the stem 34 of which is held in longitudinal sliding alignment substantially at the axial center of extension 30 by passing through guide 35 in spider 36 which is rigidly secured in any suitable manner in valve-cage coupling 37. The weight of said back pressure valve 33 and its stem 34 is carried by a spiral spring 38 which is seated on top of guide 35 and has a bearing at the upper end of said valve stem on washer 39 held in place on said valve stem by pin 40.

41 indicates a partition at the top of extension 30, and 42 a short tubular conduit opening through said partition 41 and leading to an

opening 43 in the outer face of extension 30 below packer 31.

44 diagrammatically indicates a common form of centering device, which is screw threaded to the lower end of valve-cage coupling 37. Open ports 45-45 in the drill pipe or tubing 7 above the uppermost packer are provided for the purpose hereinafter described.

Each of the packers 9, 10, 13, 31, is of a conventional type known frequently as swabs. The 10 cups 46 of the packers are of resilient material, and are adapted to be held against unlimited outward movement by retaining wires 47 which, however, do not restrain inward movement, the result being that the resilient cups 46 of said 15 packers will partially collapse inward to allow liquid to by-pass in one direction but will be restrained by the wires 47 and made to snugly fit the casing on a movement against pressure in the opposite direction. 20

48 designates a port within the cage of wires 47 of packer 10 which port extends through drill pipe or tubing 7, being controlled against inward flow of fluid by spring valve 49 secured to the outside of drill pipe or tubing 7 by rivet 50. 25

The installation and operation of the device is as follows: The tubing or drill pipe with its packers and anchoring means is lowered through the well casing and into the zone of perforations desired to be cleaned and preferably to the lowermost thereof. The drill pipe or tubing is then manipulated as above described and well known in the art to anchor packer 13 by means of the slip mechanism above described. The well tubing or drill pipe is then, through a predetermined 30 limited range, alternately raised and lowered. Upper packers 9 and 10 and bottom packer 31 being rigidly attached to the tubing, will move with the tubing upwardly and downwardly within said range of movement, on the downward movement 40 the resilient elements 46 of said packers flaring outwardly against the interior of the perforated casing to make a snug sliding fit therewith, and on the upper stroke said cups 46 partially collapsing to allow by-passing of fluid. Suction between 45 packers 10 and 13 on the upward stroke will also be neutralized by the opening of valve 49. 55

The downward movement of packers 9 and 10 will force the fluid between packer 10 and anchored packer 13 forcibly out through the zone 50 of perforations in the casing between said packers and at the same time the downward movement of packer 31 will create a suction within the perforated casing above packer 31 which will draw fluid through the perforations into the casing above said packer. Thus there will be a circulation of fluid forced outwardly through perforations between packers 10 and 13 and drawn inward through the perforations above packer 31 60 by the downward movement of said packer. 65

On the up stroke of packer 31 compression above said packer will be partially or wholly neutralized (depending upon the specific design of packer 31) by the opening of back pressure valve 65 33 which will permit compression to be relieved through ports 32 and the bottom of the drill pipe or tubing, and will also be to some extent neutralized by the partial collapse of the resilient element of the packer, if the collapsible form shown 70 and described be utilized. It will be obvious that with the lower packer so designed as to freely collapse to relieve compression above it on its upward stroke that the back pressure valve might be dispensed with and its function wholly per- 75

formed by the collapsing of the resilient element of the swab or packer 31.

Open ports 45—45, port 43 and conduit 42 permit liquid to enter and leave the portion of the tubing or drill pipe above partition 41 when said tubing or drill pipe, at the points of location of said ports, is below the fluid level in the well, that is to say, when the tubing at the points of location of said ports 45 is below the fluid level in 10 the well fluid will flow into the tubing therethrough, and when the tubing at the location of the cleaning device is raised above the fluid level, any fluid in the tubing will flow out and back into the well.

15 It will be seen that compression between the lowermost of the upper packers 9 and 10 and the anchored packer 13 and, simultaneously with said compression, suction between the anchored packer 13 and bottom packer 31 will force fluid out through the perforations above the stationary packer 13 and back through the perforations into the casing below said anchored packer 13, thus washing off the formation walls and sucking into the screen or perforated casing mud, 20 gummy substances and other debris which retard production.

It will be observed also that as the device is moved upward from one zone of perforations to another, the anchoring mechanism takes hold 30 and positions the anchored packer 13 in the new location, and that the suction, or lower part of the device, is always working on perforations that have been opened by the upper, or pressure part.

It will be quite obvious that instead of two 35 upper packers 9 and 10 a single swab or packer could be substituted with the same general result. The two packers, however, have been proven by experiment to be more efficient in supplementing the functions of each other.

40 Obviously, various other modifications, such as in the design of the packers, and their relative positions as well as in those of the slip mechanism, and in the form and location of the various ports and of the back pressure valve may be employed without departing from the spirit of my 45 invention.

What I claim and desire to cover by Letters Patent is:

1. In a device of the character described, a pair 50 of well casing packers secured in spaced relation on a string of well tubing, a third well casing packer interposed between said first mentioned pair of packers and slidably mounted on said tubing, carrying means to anchor it at a selected point within a perforated well casing, a port 55 through said tubing at a point located between said third packer and the lowermost of said first mentioned pair of packers, and means to prevent flow of fluid through said port to preserve suction 60 between said last mentioned packers.

2. In a device of the character described, a pair 65 of well casing packers secured in spaced relation on a string of well tubing, a third well casing packer interposed between said first mentioned pair of packers and slidably mounted on said tubing, carrying means to anchor it at a selected point within a perforated well casing, a port through said tubing at a point located between said third packer and the lowermost of said 70 first mentioned pair of packers, and means to prevent flow of fluid through said port during a downward movement of said lowermost packer.

3. In a device of the character described, three 75 packers each adapted to snugly and slidably fit the interior of a perforated well casing, two

of said packers being attached in spaced relation on a string of well tubing extending to the top of the well, the third of said packers being interposed between said first two packers, being 5 slideable on said well tubing, and carrying means to anchor it at any desired point within said well casing, a partition in said tubing adjacent the lowermost packer, a port in said tubing, and a back pressure valve in said tubing below 10 said lowermost packer.

4. In a device of the character described, a pair 15 of well casing packers secured in spaced relation on a string of well tubing, a third well casing packer interposed between said first mentioned pair of packers slidably mounted on said tubing and carrying means to anchor it at a selected point within a perforated well casing, said first mentioned pair of packers being reciprocable by means of said tubing, means comprising a port through said tubing above said lowermost packer and a back pressure valve in said tubing below said packer, to relieve compression 20 above said packer during its reciprocatory movement toward said anchored packer.

5. In a device of the character described, a pair 25 of well casing packers secured in spaced relation on a string of well tubing, a third well casing packer slideable on said tubing interposed between said first mentioned pair of packers and carrying means to anchor it at a selected point 30 within a perforated well casing, said first-mentioned pair of packers being adapted to be reciprocated vertically with respect to said anchored packer within a well casing.

6. In a device of the character described, three 35 packers each adapted to snugly and slidably fit the interior of a perforated well casing, two of said packers being attached in spaced relation on a string of well tubing extending to the top of the well, the third of said packers being 40 interposed between said first two packers, being slideable on said well tubing and carrying means to anchor it at any desired point within said well casing, partitioning means in said tubing dividing space above said lowermost packer 45 within said tubing from space within said tubing below said packer, a port in said tubing above said lowermost packer and a back pressure valve controlling flow into said tubing below said port.

7. In a device of the character described, a pair 50 of well casing packers secured in spaced relation on a string of well tubing, a third well casing packer slideable on said tubing interposed between said first mentioned pair of packers and carrying means to anchor it at a selected point within 55 a perforated well casing, said first mentioned pair of packers being adapted for vertical reciprocatory movement by means of said tubing with respect to the anchored packer, the uppermost packer being designed to preserve compression 60 between it and the anchored packer during its reciprocatory movement toward such anchored packer, and to by-pass pressure during its movement in an opposite direction, the lowermost of said packers being designed to preserve suction 65 between it and said anchored packer during movement from said anchored packer, and to by-pass pressure during an opposite reciprocatory movement.

8. In a device of the character described, a pair 70 of packers, a pipe for positioning said packers at a selected zone within a well, and means motivated by the downward movement of said pipe to cause relative movement of said packers and thereby create suction between said packers. 75

9. In a device of the character described, a pair of packers, a tubing for positioning said packers within a well casing, means for creating suction between said packers by the downward movement of said tubing, and means to communicate the space confined between said packers to a point below the lowermost packer.
10. In a device of the character described, a plurality of well casing packers, a tubing adapted for reciprocation to position said packers at a selected zone within a well casing, and means actuated by the tubing to relatively move said packers and thereby create pressure between one pair thereof, and suction between a second pair of said packers.
11. In a device of the character described, a casing, a plurality of packers forming annular chambers therebetween, and means to slidably position said packers in the casing to permit relative reciprocation therebetween to enlarge one of said chambers and contract another of said chambers.
12. In a device of the character described, a casing, a plurality of packers forming annular chambers therebetween, means to slidably position said packers in the casing to permit relative reciprocation therebetween, and means to relieve pressure created in one of said chambers and means to relieve vacuum created in another of said chambers.
13. The method of cleaning a perforated pipe which comprises packing off a series of areas in said pipe to be cleaned and applying suction to one packed-off area and pressure to another packed-off area.
14. The method of cleaning perforated pipe which comprises plugging the pipe at the point desired to be cleaned, packing off an area above and below the point of plugging, and simultaneously reducing and enlarging the packed-off areas.
